UNITED STATES PATENT OFFICE

2,616,009

MECHANISM FOR OPERATING A MOMENTARY SWITCH FOR AN ELECTRIC CIRCUIT

John O. Roeser, Chicago, Ill., assignor to The Exhibit Supply Co., Chicago, Ill., a corporation of Illinois

Application August 10, 1950, Serial No. 178,678

7 Claims. (Cl. 200—160)

1

This invention relates to certain new and useful improvements in a mechanism for operating a momentary switch for an electric circuit, that is, a switch which is momentarily closed.

The invention has for its principal object, to provide a simplified and effective arrangement for momentarily closing a switch.

Other objects will appear hereinafter.

The invention consists in the novel combination and arrangement of parts to be hereinafter described and claimed.

The invention will be best understood by reference to the accompanying drawings showing the preferred form of construction, and in which:

Fig. 1 is a vertical sectional detail view of the invention;

Fig. 2 is a sectional detail view similar to Fig. 1 showing the parts in switch closing position;

Fig. 3 is a sectional detail view showing the parts thereof partially returned from switch closing position; and

Fig. 4 is a perspective view similar to Fig. 3 showing the parts thereof in position just prior to return to initial starting positions.

The objects of this invention are accomplished by providing a casing or housing 10 within which is arranged the switch 11 and the mechanism for momentarily closing the switch.

This switch 11 constitutes in itself no part of the present invention and is of a construction well known in the art and which construction includes an actuating button 11.

The housing 10 provides an extension 12 having a central bore 13 formed therein. Fixedly mounted in this bore 13 is a guiding sleeve 14. Mounted for reciprocation in the sleeve 14 is a plunger 15. The inner end portion of this plunger 15 provides a counter bore 16. Arranged in this counter bore 16 is an expansion spring 17. This expansion spring 17 embraces a pin 18 carried by the wall 19 of the housing 10. The spring 17 functions to project the plunger 15 to its outermost position with respect to the sleeve 14 as shown in Fig. 1. Embracing the plunger 15 is a stop collar 20 which limits the outward movement of the plunger 15 with respect to the sleeve 13. The intermediate or medial portion of the plunger 15 provides reduced portions 21 and 22 separated by an enlarged or raised portion 23.

The wall 24 of the housing provides spaced lugs 25 in which is journaled a pintle 26. This pintle 26 works in a slot 27 formed diagonally in the side walls 28 of an operating lever 29. This operating lever 29 has an extended portion 55

30 adapted to engage the button 12 of the switch 11. Supported by and arranged between the side walls 28 is a roller 31 which normally engages in the groove 32 provided by reducing the plunger 15 to provide the reduced portion 22.

The wall 19 carries a bolt 33 to which one end portion 34 of a spring 35 is connected. The opposite end portion 36 of the spring 35 is connected to the extended portion 30 of the lever 29.

The housing 10 provides a conduit 37 through which the conductor wires to the switch 11 are passed.

The arrangement is such that when the plunger 15 is moved inwardly against the action of the spring 17 the raised portion 23 thereof will (as shown in Fig. 2) engage the roller 31 and pivot the lever 29 about the pintle 26 to bear the extended portion 30 of such lever on the button 12. As the roller rides over the raised portion 23 the switch (as shown in Fig. 2) will be closed and as the roller passes from engagement with the raised portion 23 and moves into the groove 32 provided by the reduced portion 21 the button 12 will instantly return to its original position thus to effect the momentary closing of the switch 11. Upon release of the plunger 15 for return to its initial starting position under action of the spring 17 the raised portion 23 (as shown in Fig. 3) will engage the roller 31. Such engagement between the roller 31 and the raised portion 23 will bear the pintle 26 against the top edge of the slot 27 and by reason of the diagonal position of the slot 27 this bearing action of the pin upon the edge of such slot will shift the lever 29 to the position shown in Fig. 4, in which position, as the raised portion 23 passes over the roller 31 it will not effect a bearing action of the extension 30 on the button 12 to close the switch 11. By this arrangement the switch is closed only upon inward movement of the plunger and then only momentarily.

My invention will be especially useful in apparatuses or in electric circuits where it is desirable that a switch be momentarily closed.

The invention is simple in construction and by reason thereof may be manufactured at an economical cost.

While I have illustrated and described the preferred form of construction for carrying my invention into effect, this is capable of variation and modification without departing from the spirit of the invention. I, therefore, do not wish to be limited to the precise details of construction set forth, but desire to avail myself of such

variations and modifications as come within the scope of the appended claims.

Having thus described my invention, what I claim as new and desire to protect by Letters Patent is:

1. A mechanism for momentarily closing a switch comprising a housing within which said switch is arranged, a plunger mounted for reciprocation in said housing, spring means engaging said housing and said plunger for moving said plunger relative to said housing in one direction, said plunger having a medial portion reduced to provide circumferential grooves and an enlarged portion separating said grooves, a lever having an end portion engaging a button of said switch, a slot and pin connection between the lever and the housing with the slot of said connection extending diagonally with respect to the lever, and a roller carried by the lever for riding engagement with said enlarged portion for movement into said grooves and adapted to engage with said enlarged portion when said plunger is moved in an opposite direction to bear said end portion against said button to close said switch and to move said lever transversely of the long axis of the pin of said connection when said plunger is moved in said one direction.

2. A mechanism for momentarily closing a switch comprising a housing within which said switch is arranged, a plunger mounted for reciprocation in said housing, spring means engaging said housing and said plunger for moving said plunger relative to said housing in one direction, said plunger having a medial portion reduced to provide circumferential grooves and an enlarged portion separating said grooves, a lever having an end portion engaging a button of said switch, a slot and pin connection between the lever and the housing with the slot of said connection extending diagonally with respect to the lever, a roller carried by the lever for riding engagement with said enlarged portion for movement into said grooves and adapted to engage with said enlarged portion when said plunger is moved in an opposite direction to bear said end portion against said button to close said switch and to move said lever transversely of the long axis of the pin of said connection when said plunger is moved in said one direction, and spring means for urging movement of said lever in one longitudinal direction.

3. A mechanism for momentarily closing a switch comprising a housing within which said switch is arranged, a plunger mounted for reciprocation in said housing, spring means engaging said housing and said plunger for moving said plunger relative to said housing in one direction, said plunger having a medial portion reduced to provide circumferential grooves and an enlarged portion separating said grooves, a lever having an end portion engaging a button of said switch, a slot and pin connection between the lever and the housing with the slot of said connection extending diagonally with respect to the lever, and means carried by the lever and having riding engagement with said enlarged portion for movement into said grooves and adapted to engage with said enlarged portion when said plunger is moved in an opposite direction to bear said end portion against said button to close said switch and to move said lever transversely of the long axis of the pin of said connection when said plunger is moved in said one direction.

4. A mechanism for momentarily closing a switch comprising a housing within which said switch is arranged, a plunger mounted for reciprocation in said housing, spring means engaging said housing and said plunger for moving said plunger relative to said housing in one direction, said plunger having a medial portion reduced to provide circumferential grooves and an enlarged portion separating said grooves, a lever having an end portion engaging a button of said switch, a slot and pin connection between the lever and the housing with the slot of said connection extending diagonally with respect to the lever, means carried by the lever and having riding engagement with said enlarged portion for movement into said grooves and adapted to engage with said enlarged portion when said plunger is moved in an opposite direction and to bear said end portion against said button to close said switch and to move the lever transversely of the long axis of the pin of said connection when said plunger is moved in said one direction, and spring means for urging movement of said lever in one longitudinal direction.

5. A mechanism for momentarily closing a switch comprising a housing within which said switch is arranged, a plunger mounted for reciprocation in said housing, spring means engaging said housing and said plunger for moving said plunger relative to said housing in one direction, said plunger having a medial portion reduced to provide circumferential grooves and an enlarged portion separating said grooves, a lever having an end portion engaging a button of said switch, means providing a connection between the lever and the housing to permit pivotal and transverse movement of the lever with respect to the connecting means, a roller carried by the lever and having riding engagement with said enlarged portion for movement into said grooves and adapted to engage with said enlarged portion when said plunger is moved in an opposite direction to bear said end portion against said button to close said switch and to move the lever transversely of the long axis of said connecting means between said lever and said housing when said plunger is moved in said one direction.

6. A mechanism for momentarily closing a switch comprising a housing within which said switch is arranged, a plunger mounted for reciprocation in said housing, spring means engaging said housing and said plunger for moving said plunger relative to said housing in one direction, said plunger having a medial portion reduced to provide circumferential grooves and an enlarged portion separating said grooves, a lever having an end portion engaging a button of said switch, means providing a connection between the lever and the housing to permit pivotal and transverse movement of the lever with respect to the connecting means, a roller carried by the lever and having riding engagement with said enlarged portion for movement into said grooves and adapted to engage with said enlarged portion when said plunger is moved in an opposite direction and to bear said end portion against said button to close said switch and to move said lever transversely of the long axis of said connecting means between said lever and said housing when said plunger is moved in said one direction, and spring means for urging movement of said lever in one longitudinal direction.

7. A mechanism for momentarily closing a switch comprising a housing within which said

switch is arranged, a plunger mounted for reciprocation in said housing, spring means engaging said housing and said plunger for moving said plunger relative to said housing in one direction, said plunger having a medial portion reduced to provide circumferential grooves and an enlarged portion separating said grooves, a lever having an end portion engaging a button of said switch, means providing a connection between the lever and the housing to permit pivotal and transverse movement of the lever with respect to the connecting means, means carried by the lever and having riding engagement with said enlarged portion for movement into said grooves and adapted to engage with said enlarged portion 15 when said plunger is moved in an opposite direc-

tion and to bear said end portion against said button to close said switch and to move said lever transversely of the long axis of said connecting means between said lever and said housing when said plunger is moved in said one direction.
